UNITED STATES PATENT OFFICE

2,415,437

TELEPHONE EXCHANGE APPARATUS

Frank R. McBerty, Mansfield, Ohio, assignor to
The North Electric Manufacturing Company,
Galion, Ohio, a corporation of Ohio

Application July 29, 1940, Serial No. 348,223

57 Claims. (Cl. 179—25)

1

My invention relates, generally, to telephone exchange apparatus, and it has particular relation to automatic telephone exchange apparatus of the all relay type such as described in "Telephone Theory and Practice," by Kempster B. Miller, first edition, 1933, chapter VI.

An object of my invention is to reduce to a minimum the space required by the relays and conductors in telephone exchange apparatus.

Another object of my invention is to so arrange the terminals of the relays that connections thereto can be made by substantially straight conductors.

A further object of my invention is to arrange the sets of terminals of the relays that are multiplied with the portions to which connection is made in straight lines so as to permit the multiplied connections to be made by straight conductors.

Still another object of my invention is to arrange the units and tens relays of each link in tandem on a support member with the portions of the sets of terminals that are connected in multiple arranged in straight lines to permit interconnection by straight conductors.

It is another object of my invention to arrange the links in side-by-side relation with the terminals of each link that are to be connected in multiple with the corresponding ones of the other links arranged in straight lines to permit interconnection by straight conductors.

It is still another object of my invention to arrange the units and tens relays of each link in tandem on a support member and the links in side-by-side relation with the portions of the sets of terminals of each link that are to be connected in multiple, and of the terminals of each link that are to be connected in multiple with the corresponding ones of the other links arranged in straight lines to permit interconnection by straight conductors.

Other objects of my invention will, in part, be obvious and in part appear hereinafter.

My invention, accordingly, is disclosed in the embodiments thereof shown in the accompanying drawings, and it comprises the features of construction, combination of elements, and arrangement of parts which will be exemplified in the constructions hereinafter set forth, and the scope of the application of which will be indicated in the appended claims.

For a more complete understanding of the nature and scope of my invention, reference may be had to the following detailed description taken

2

in connection with the accompanying drawings, in which:

Figure 1 is a view, in front elevation, of a frame showing somewhat diagrammatically the arrangement of ten line finder links and ten line connector links for a one hundred line all relay type of automatic telephone exchange, no attempt being made to show the details of relay construction or the arrangement of the connections because of the small scale employed;

Figure 2 is a sectional view taken along the line 2—2 of Figure 1, again showing somewhat diagrammatically the details of construction;

Figure 3 is a view, in front elevation, of the front terminal strip of one of the links;

Figure 4 is a view, in front elevation, of the ten units relays of one of the links;

Figure 5 is a view, in front elevation, of two of the ten tens relays of one of the links;

Figure 6 is a view, in side elevation, of the two terminal strips for each link;

Figure 7 is a view, in side elevation, of the ten units relays for each link;

Figure 8 is a view, in side elevation, of two of the ten tens relays of each link;

Figures 9 and 10 are detail sectional views showing different types of relay construction that can be employed for the units and tens relays; and

Figure 11 is a rear elevation of two tens relays of adjacent links showing the arrangement of the conductors by means of which corresponding terminals of the tens relays of the different links are multiplied.

Referring now particularly to Figures 1 and 2 of the drawings, it will be observed that the reference character 10 designates, generally, a rectangular frame that is formed by upright side members 11 and interconnecting top and bottom members 12. As shown, the members 11 and 12 are angles, but it will be understood that any other suitable type of frame members can be employed, such as channels, etc. The frame members are fastened together by any suitable means such as welding.

The members 12 are arranged to support links which are shown generally at 15. Twenty links 15 have been illustrated, ten of them being line finder links, and the remaining ten being line connector links. It will be understood, however, that greater or lesser numbers of links can be employed depending upon the service required and the number of lines involved, the construction shown being that which has been found particularly suitable for ordinary purposes in con-

nection with a one hundred line telephone exchange.

In so far as the structural arrangements are concerned, all of the links 15 are duplicates of each other. Accordingly, a description of one will suffice for all of them. Each link 15 comprises a support member 16 in the form of a back bar which, as will be hereinafter set forth, may form a part of the magnetic circuit of the relays, or it may be employed solely as a support member for the relays which may be provided with self-contained magnetic circuits. The support members 16 are vertically positioned, as shown, in side-by-side relationship with the other support members of adjacent links, and are arranged to have mounted thereon a group of ten units relays 17 and a group of ten tens relays 18. The units and tens relays 17 and 18 are mounted in tandem on the support members 16, with the units relays 17 at the top and the tens relays 18 below. The details of construction of the units and tens relays 17 and 18 will be set forth in detail hereinafter.

Certain of the terminals of the units and tens relays 17 and 18 of each link 15 are connected in multiple to terminal strips 19 and 20 at the upper end of the support member 16. Certain other terminals of the units and tens relays 17 and 18 which are not multiplied, are likewise connected to the terminal strips 19 and 20 by conductors which are known as control conductors.

Intermediate the frame members 12 is a channel member 21 that is arranged to carry terminal strips 22 which are common to all of the line finder and connector links 15. Certain of the terminals of the units and tens relays 17 and 18 are connected in multiple with corresponding ones of the relays of adjacent links and are also connected to the terminal strips 22 to which the incoming lines are connected, as is readily understood by those skilled in the art. While the terminal strips 22 which are common to the line finder and connector links 15 are illustrated as being positioned intermediate these two groups of links, it will be understood that the terminal strips 22 can be positioned at either end of the frame 10 with the links 15 then being spaced uniformly apart on the frame 10 instead of their being formed into two groups with the terminal strips 22 therebetween as illustrated. In either construction the electrical connections would be the same.

As indicated hereinbefore, the details of construction of the line finder and connector links 15 are identical. The circuit connections thereto will, of course, be in accordance with the particular system arrangement that is employed and the operating features that are desired. Therefore, a description of the details of construction of one of the links 15 and the arrangement of the connections thereto will suffice for all of the links.

Referring now to Figures 3 and 6 of the drawings, it will be observed that the construction of the terminal strips 19 and 20 is shown in detail. These terminal strips each comprise insulating strips 25 and 26 which are mounted by suitable brackets 27 and 28 on opposite sides of the support member or back bar 16. The insulation strips 25 and 26 are identical and are each provided with four rows of terminal lugs shown generally at 29 and 30, to which groups of conductors 31 and 32 are connected as illustrated. It will be understood that certain of the conductors 31 and 32 serve to connect certain of the

5 terminals of the relays of the particular link in multiple and certain other of them are directly connected to certain other terminals and constitute control conductors. Guide and spacing members 33 and 34, of suitable insulating material, such as a thermoplastic material known as "polystyrene," are provided at spaced intervals along the conductors 31 and 32 for supporting them in insulated spaced relation.

As will hereinafter appear, the arrangement of the terminals of the relays is such that the conductors 31 and 32 are positioned substantially in straight lines. This arrangement of the conductors substantially decreases the capacity therebetween, since bare conductors are employed with the dielectric therebetween being air except for the support members 33 and 34. Because of this reduction in capacity between the conductors over that which exists when twisted pairs of conductors are employed, the noise level of the circuits is materially reduced.

The conductors 31 and 32 are preferably formed of non-corrosive material such as stainless steel, and they may have a diameter of 0.020 inch.

Extending from each of the insulating strips 25 and 26 is a pair of plate-like insulating members 35 and 36 provided with apertures 37 and 38 respectively, through which the external conductors can be passed for connection to the appropriate terminal lugs 29 and 30.

The details of construction of the units and tens relays 17 and 18 are fully set forth in my copending application Serial No. 348,222, filed July 29, 1940, now Patent No. 2,396,332, dated 35 March 12, 1946, and, accordingly, will not be repeated herein. Only a sufficient description of the details of the relay construction will be set forth herein as will provide a complete understanding of the present invention. Before proceeding with a description of the units and tens relays 17 and 18 as they are assembled in the link 15, reference will first be had to Figures 9 and 10 of the drawings which show alternate types of relay construction that may be employed for either the units or the tens relays.

Referring first to Figure 9 of the drawings, it will be noted that a portion of the magnetic circuit is formed by the back bar or support member 16. It comprises a portion of a generally U shaped magnetic member, the sides of which are formed by side pole pieces 41. It has already been noted that the support member 16 extends throughout the entire length of the link and that it is common to all of the relays. The side pole pieces 41 are likewise common to all of the relays, so that the generally U shaped magnetic member formed by the support member 16 and the side members 41 is common to all of the units and tens relays 17 and 18. Cooperating with the U shaped magnetic member is a generally T shaped magnetic member formed by a core 42 which comprises the stem of the T, and a top member 43, the ends of which are spaced from the ends of the U shaped magnetic member or the upper edges of the side magnetic members 41 to form air gaps 44 therebetween. A winding 45 is located around the core 42 or around the stem of the T-shaped magnetic member for energizing the magnetic circuit, as will be readily understood.

Associated with each of the air gaps 44 is a set of movable and stationary cooperating contact members. Each of the movable contact members comprises a metallic reed 46 which carries a contact member 47 or armature at its upper end for

contact engagement with a cooperating stationary contact member 48 that is molded in a suitable strip 49 of insulating material and has a terminal portion 50 which projects upwardly therefrom. The metallic reeds 46 are supported intermediate their ends by being molded in strips 51 of suitable insulating material. Preferably, the strips 49 and 51 are formed of thermoplastic material, such as "polystyrene." The lower ends 52 of the metallic reeds 46 constitute terminals to which conductors can be attached, as will be readily understood.

The metallic reeds 46 are spring-like in character and are so arranged that normally they urge the contact members or armatures 47 carried thereby away from the air gaps 44. It is desirable that the armatures 47 be spaced uniformly from their cooperating stationary contact members 48. For this purpose, stop members 53 in the form of glass rods are positioned along the backs of the armatures 47 and serve to provide the desired alignment. The glass rods 53 extend the full length of all of the units and tens relays 17 and 18, and thereby accurately align all of the armatures 47. It will be observed that the relays herein described after they are assembled have no adjustment whatever. The glass rods 53 are of particular significance in this connection. They are straight and remain permanently so, and do not change shape or size under variations of temperature or humidity. They avoid any tendency of the armatures to stick to them. The round glass rod has substantially only line contact with the back of the armature and hence minimum tendency to stick or slow down the motion of the armature in either direction. The common and uniform spacing of the armatures relative to their contacts by means of the glass rods is particularly important for multiple relays such as the present where a relatively large number of armatures are employed, and wherein a very small gap between the movable and stationary contacts is desired.

The armatures 47 serve a dual purpose. They carry current between the stationary contact members 48 and the associated metallic reeds 46. In addition, since they are formed of magnetic material, they are attracted toward the air gaps 44 on energization of the winding 45 to cause the desired contact engagement.

In Figure 10 of the drawings, an alternate relay construction is shown. In this construction, the back bar or support member 16 serves only a single function, i. e., it supports the units and tens relays 17 and 18. The U shaped magnetic member is provided by the self-contained U shaped magnetic member 54 in which the bottom and the sides are integral. The U shaped magnetic member 54 may be common to all of the units and tens relays, or it may be individual thereto, or it may be individual to groups of these relays, for example it may be individual to ten of the units relays 17 and to two of the tens relays 18.

Referring now to Figures 4 and 7 of the drawings which show the arrangement of the ten units relays 17 in a link, it will be noted that the insulating strip 49 in which the stationary terminals 48 are molded extends over the entire group of relays. The terminal extensions 50 are arranged in coplanar relationship with the extreme outer ends turned outwardly or inwardly, depending upon the particular connections that are to be made thereto. It will also be noted that the terminal extensions 50 are of different lengths,

or are staggered, so as to permit connection thereto without interference from the other connections. In general, it may be stated that all of the portions of the terminal extensions 50 which are to be connected together, or are to be multiplied, are arranged substantially in a straight line so that a substantially straight conductor can interconnect them.

As shown more clearly in Figure 7 of the drawings, the terminal portions 52 of the metallic reeds 46 extend at variable distances below the support member 51 therefor, depending upon the connections that are made thereto. It will be observed that the metallic reeds 46 and their terminal extensions 52 are arranged in coplanar relationship, and that they extend beyond the support member 16 in a direction which is opposite to the direction in which the terminal portions 50 of the stationary contact members 48 extend. In order to avoid short circuiting of the various terminal extensions 52, connectors 55 which extend at right angles to the plane of the paper on which Figure 7 is shown serve to interconnect them with the corresponding ones of the group of conductors 32, as will be readily understood.

Referring now particularly to Figures 5 and 8 of the drawings, it will be observed that the arrangement and the connections to the tens relays 18 are generally the same as described for the units relays 17. As shown in Figure 5, the insulation support member 49 is common to two of the tens relays 18. The terminal extensions 50 carried thereby have certain of their outer ends turned outwardly and others turned inwardly, depending upon the connections that are to be made thereto. The terminal extensions 50 on the opposite sides of the insulating support member 49 are arranged in coplanar relationship and, as shown in Figure 8, they are staggered in order to permit connection to the conductors 31 without interference. In general it may be stated that here, as for the units relays, the portions of the terminal extensions 50 that are multiplied or connected together are arranged in straight lines so that the conductors 31 interconnecting the same can likewise be arranged in straight lines.

The extensions 52 from the metallic reeds 46 project beyond the support member 16 and are arranged in coplanar relationship as previously described for the units relays 17. Certain of the terminal portions 52 are connected by the conductors 32 to the terminal strip 20 associated with the particular link. The remaining ones of the terminal projections 52 are connected to corresponding ones of the tens relays on the adjacent links in a manner which will now be described.

Referring now to Figure 11 of the drawings, it will be observed that portions of two adjacent links are illustrated showing the cross connections or common multiple connections between the tens relays 18. As previously described, the portions 52 of the metallic reeds 46 which project beyond the support member or back bar 16 constitute terminal connecting portions for the movable contact members. The reeds 46 are mounted intermediate their ends in insulating strips 51 which are secured to the edges of the back bar or support member 16 by means of suitable screws 56. These screws also support clamp members 57 which carry the conductor spacer and guide members 34.

Certain of the terminal portions 52 of the metallic reeds 46 are multiplied with corresponding ones of the tens relays of adjacent links. As

shown in Figure 11, the terminal portions 52 on opposite sides of each link are located in staggered relation so that they can be interconnected by straight conductors 60. It will be apparent that the portions of the terminals 52 to which the conductors 60 are connected on the various links are arranged in straight lines so that the conductors 60 can also follow this straight line pattern. All of the conductors 60 are arranged in coplanar relationship and are mounted in insulated spaced relation by conductor supports and spacers 61 that are formed of suitable insulating material, such as a thermoplastic material known as "polystyrene." The members 61 are generally T shaped in construction, with the conductors 60 being threaded through suitable apertures in the stem 62 of the T.

The general operation of my device will now be briefly outlined for the purpose of indicating more fully the utility of the various units illustrated and described. In an exchange employing my selector-connector unit the telephone lines to subscribers are connected to the multiple conductors 60 of which in the illustrated unit there are ten banks of ten lines, each line including the two talking conductors and one testing conductor. An incoming call on a line operating through a suitable starter wire and control circuits automatically finds an idle link, which comprises a selector unit 15 at the left of Figure 1 and a cooperating connector unit 15 at the right of Figure 1. In the selector unit the tens relay 18 to which the tens of the calling line number corresponds and the corresponding units relay 17 out of the group of ten units relays of that selector to which the units of the calling line number corresponds are energized. This is done through known relay selection and is completed almost instantly upon closing of the calling line circuit. The calling subscriber dials the tens digits of the called number and a system of counting relays receives the tens impulses and energizes in the connector unit the corresponding tens relay 18 to which the called line number and position corresponds. Then the dialing of the units digits of the called number similarly is received by the counting relays and the corresponding connector unit relay 17 energized, subject to the busy test of the line called, to close the connection to the called line, and to apply the ringing current automatically. It is thus seen that the tens and units selection for line finding and for connection is performed by an exceedingly compact mechanism employing very short runs of bare conductor. The result of my invention is an exchange of unusually low cost, of long life and excellent performance. The noise level in an exchange of this character is far below that of any previously known exchange, largely because of the freedom from the considerable lengths of twisted pairs of talking conductors heretofore invariably employed in an exchange of the all-relay type, as well as in the travelling contact type. The particular form of selector-connector relays employed avoids noise at the relay contacts where heretofore considerable disturbance has originated.

Since certain further changes can be made in the foregoing constructions and different embodiments of the invention can be made without departing from the spirit and scope thereof, it is intended that all matter shown in the accompanying drawings and described hereinbefore shall be interpreted as illustrative and not in a limiting sense.

In the following claims, the terms "vertical" and "horizontal" are employed for convenience to indicate relative directions, namely, at right angles to each other in a common plane, and are not intended to imply that the parts which are defined as lying or extending in those positions or directions must be placed or extended in such vertical or horizontal position or direction, or in any particular position or direction, so long as the relative position or direction in space is maintained. Similarly, upper and lower and inner and outer are used for convenience to indicate relative and not absolute position. In brief, the use of terms indicating direction or position is relative and not absolute. This is particularly to be observed since in use the relay is in a telephone installation generally disposed with the axis of its core in a horizontal position.

I claim as my invention:

20. 1. A multi-relay assembly comprising, in combination, a bar supported at its ends and constituting a support member, and a plurality of aligned relays carried by said support member; each relay including a winding, a magnetic circuit providing an air gap having its length extending longitudinally of said supporting bar, stationary and movable contact means, and terminals extending from said contact means to opposite front and back sides of said support member, certain corresponding sets of which terminals on the front side are connected in multiple, the portions of each set of multiplied terminals to which multiple connection is made being located substantially in a straight line a single substantially straight bare link conductor extending longitudinally of said bar for interconnecting each set of aligned terminals; and terminal strips disposed at one end of and lying on opposite sides of said support member and bearing terminal conductors to which said sets of multiplied terminals and certain of the remaining terminals are connected for making connections outside the aforesaid assembly.
25. 2. A multi-relay assembly comprising, in combination, a bar constituting a support member, and a plurality of aligned relays carried by said support member; each relay including a winding, a magnetic circuit providing an air gap having its length extending longitudinally of said supporting bar, stationary and movable contact means, and terminals extending from said stationary contact means away from said support member and in front of the same, said movable contact means comprising conducting reeds stationarily mounted intermediate their ends and carrying said movable contact members at one end to cooperate with said stationary contact means while the other ends form terminals and extend beyond said support member in a direction opposite to that in which the terminals from said stationary contact means extend, certain sets of said terminals being connected in multiple, the portions of each set of multiplied terminals to which connection is made being located substantially in a straight line longitudinally of the bar, a single substantially straight conductor extending longitudinally of said bar for interconnecting said set of aligned terminals; and terminal strips disposed at one end of and lying on opposite sides of said support member providing terminal conductors to which said sets of multiplied terminals and certain of the remaining terminals are connected for making connections outside said assembly.
30. 3. A multi-relay assembly comprising, in combination, a bar supported at its ends and constituting a support member, and a plurality of aligned relays carried by said support member; each relay including a winding, a magnetic circuit providing an air gap having its length extending longitudinally of said supporting bar, stationary and movable contact means, and terminals extending from said stationary contact means away from said support member and in front of the same, said movable contact means comprising conducting reeds stationarily mounted intermediate their ends and carrying said movable contact members at one end to cooperate with said stationary contact means while the other ends form terminals and extend beyond said support member in a direction opposite to that in which the terminals from said stationary contact means extend, certain sets of said terminals being connected in multiple, the portions of each set of multiplied terminals to which connection is made being located substantially in a straight line longitudinally of the bar, a single substantially straight conductor extending longitudinally of said bar for interconnecting said set of aligned terminals; and terminal strips disposed at one end of and lying on opposite sides of said support member providing terminal conductors to which said sets of multiplied terminals and certain of the remaining terminals are connected for making connections outside said assembly.
35. 4. A multi-relay assembly comprising, in combination, a bar supported at its ends and constituting a support member, and a plurality of aligned relays carried by said support member; each relay including a winding, a magnetic circuit providing an air gap having its length extending longitudinally of said supporting bar, stationary and movable contact means, and terminals extending from said stationary contact means away from said support member and in front of the same, said movable contact means comprising conducting reeds stationarily mounted intermediate their ends and carrying said movable contact members at one end to cooperate with said stationary contact means while the other ends form terminals and extend beyond said support member in a direction opposite to that in which the terminals from said stationary contact means extend, certain sets of said terminals being connected in multiple, the portions of each set of multiplied terminals to which connection is made being located substantially in a straight line longitudinally of the bar, a single substantially straight conductor extending longitudinally of said bar for interconnecting said set of aligned terminals; and terminal strips disposed at one end of and lying on opposite sides of said support member providing terminal conductors to which said sets of multiplied terminals and certain of the remaining terminals are connected for making connections outside said assembly.
40. 5. A multi-relay assembly comprising, in combination, a bar supported at its ends and constituting a support member, and a plurality of aligned relays carried by said support member; each relay including a winding, a magnetic circuit providing an air gap having its length extending longitudinally of said supporting bar, stationary and movable contact means, and terminals extending from said stationary contact means away from said support member and in front of the same, said movable contact means comprising conducting reeds stationarily mounted intermediate their ends and carrying said movable contact members at one end to cooperate with said stationary contact means while the other ends form terminals and extend beyond said support member in a direction opposite to that in which the terminals from said stationary contact means extend, certain sets of said terminals being connected in multiple, the portions of each set of multiplied terminals to which connection is made being located substantially in a straight line longitudinally of the bar, a single substantially straight conductor extending longitudinally of said bar for interconnecting said set of aligned terminals; and terminal strips disposed at one end of and lying on opposite sides of said support member providing terminal conductors to which said sets of multiplied terminals and certain of the remaining terminals are connected for making connections outside said assembly.
45. 6. A multi-relay assembly comprising, in combination, a bar supported at its ends and constituting a support member, and a plurality of aligned relays carried by said support member; each relay including a winding, a magnetic circuit providing an air gap having its length extending longitudinally of said supporting bar, stationary and movable contact means, and terminals extending from said stationary contact means away from said support member and in front of the same, said movable contact means comprising conducting reeds stationarily mounted intermediate their ends and carrying said movable contact members at one end to cooperate with said stationary contact means while the other ends form terminals and extend beyond said support member in a direction opposite to that in which the terminals from said stationary contact means extend, certain sets of said terminals being connected in multiple, the portions of each set of multiplied terminals to which connection is made being located substantially in a straight line longitudinally of the bar, a single substantially straight conductor extending longitudinally of said bar for interconnecting said set of aligned terminals; and terminal strips disposed at one end of and lying on opposite sides of said support member providing terminal conductors to which said sets of multiplied terminals and certain of the remaining terminals are connected for making connections outside said assembly.
50. 7. A multi-relay assembly comprising, in combination, a bar supported at its ends and constituting a support member, and a plurality of aligned relays carried by said support member; each relay including a winding, a magnetic circuit providing an air gap having its length extending longitudinally of said supporting bar, stationary and movable contact means, and terminals extending from said stationary contact means away from said support member and in front of the same, said movable contact means comprising conducting reeds stationarily mounted intermediate their ends and carrying said movable contact members at one end to cooperate with said stationary contact means while the other ends form terminals and extend beyond said support member in a direction opposite to that in which the terminals from said stationary contact means extend, certain sets of said terminals being connected in multiple, the portions of each set of multiplied terminals to which connection is made being located substantially in a straight line longitudinally of the bar, a single substantially straight conductor extending longitudinally of said bar for interconnecting said set of aligned terminals; and terminal strips disposed at one end of and lying on opposite sides of said support member providing terminal conductors to which said sets of multiplied terminals and certain of the remaining terminals are connected for making connections outside said assembly.
55. 8. A multi-relay assembly comprising, in combination, a bar supported at its ends and constituting a support member, and a plurality of aligned relays carried by said support member; each relay including a winding, a magnetic circuit providing an air gap having its length extending longitudinally of said supporting bar, stationary and movable contact means, and terminals extending from said stationary contact means away from said support member and in front of the same, said movable contact means comprising conducting reeds stationarily mounted intermediate their ends and carrying said movable contact members at one end to cooperate with said stationary contact means while the other ends form terminals and extend beyond said support member in a direction opposite to that in which the terminals from said stationary contact means extend, certain sets of said terminals being connected in multiple, the portions of each set of multiplied terminals to which connection is made being located substantially in a straight line longitudinally of the bar, a single substantially straight conductor extending longitudinally of said bar for interconnecting said set of aligned terminals; and terminal strips disposed at one end of and lying on opposite sides of said support member providing terminal conductors to which said sets of multiplied terminals and certain of the remaining terminals are connected for making connections outside said assembly.
60. 9. A multi-relay assembly comprising, in combination, a bar supported at its ends and constituting a support member, and a plurality of aligned relays carried by said support member; each relay including a winding, a magnetic circuit providing an air gap having its length extending longitudinally of said supporting bar, stationary and movable contact means, and terminals extending from said stationary contact means away from said support member and in front of the same, said movable contact means comprising conducting reeds stationarily mounted intermediate their ends and carrying said movable contact members at one end to cooperate with said stationary contact means while the other ends form terminals and extend beyond said support member in a direction opposite to that in which the terminals from said stationary contact means extend, certain sets of said terminals being connected in multiple, the portions of each set of multiplied terminals to which connection is made being located substantially in a straight line longitudinally of the bar, a single substantially straight conductor extending longitudinally of said bar for interconnecting said set of aligned terminals; and terminal strips disposed at one end of and lying on opposite sides of said support member providing terminal conductors to which said sets of multiplied terminals and certain of the remaining terminals are connected for making connections outside said assembly.
65. 10. A multi-relay assembly comprising, in combination, a bar supported at its ends and constituting a support member, and a plurality of aligned relays carried by said support member; each relay including a winding, a magnetic circuit providing an air gap having its length extending longitudinally of said supporting bar, stationary and movable contact means, and terminals extending from said stationary contact means away from said support member and in front of the same, said movable contact means comprising conducting reeds stationarily mounted intermediate their ends and carrying said movable contact members at one end to cooperate with said stationary contact means while the other ends form terminals and extend beyond said support member in a direction opposite to that in which the terminals from said stationary contact means extend, certain sets of said terminals being connected in multiple, the portions of each set of multiplied terminals to which connection is made being located substantially in a straight line longitudinally of the bar, a single substantially straight conductor extending longitudinally of said bar for interconnecting said set of aligned terminals; and terminal strips disposed at one end of and lying on opposite sides of said support member providing terminal conductors to which said sets of multiplied terminals and certain of the remaining terminals are connected for making connections outside said assembly.
70. 11. A multi-relay assembly comprising, in combination, a bar supported at its ends and constituting a support member, and a plurality of aligned relays carried by said support member; each relay including a winding, a magnetic circuit providing an air gap having its length extending longitudinally of said supporting bar, stationary and movable contact means, and terminals extending from said stationary contact means away from said support member and in front of the same, said movable contact means comprising conducting reeds stationarily mounted intermediate their ends and carrying said movable contact members at one end to cooperate with said stationary contact means while the other ends form terminals and extend beyond said support member in a direction opposite to that in which the terminals from said stationary contact means extend, certain sets of said terminals being connected in multiple, the portions of each set of multiplied terminals to which connection is made being located substantially in a straight line longitudinally of the bar, a single substantially straight conductor extending longitudinally of said bar for interconnecting said set of aligned terminals; and terminal strips disposed at one end of and lying on opposite sides of said support member providing terminal conductors to which said sets of multiplied terminals and certain of the remaining terminals are connected for making connections outside said assembly.
75. 12. A multi-relay assembly comprising, in combination, a bar supported at its ends and constituting a support member, and a plurality of aligned relays carried by said support member; each relay including a winding, a magnetic circuit providing an air gap having its length extending longitudinally of said supporting bar, stationary and movable contact means, and terminals extending from said stationary contact means away from said support member and in front of the same, said movable contact means comprising conducting reeds stationarily mounted intermediate their ends and carrying said movable contact members at one end to cooperate with said stationary contact means while the other ends form terminals and extend beyond said support member in a direction opposite to that in which the terminals from said stationary contact means extend, certain sets of said terminals being connected in multiple, the portions of each set of multiplied terminals to which connection is made being located substantially in a straight line longitudinally of the bar, a single substantially straight conductor extending longitudinally of said bar for interconnecting said set of aligned terminals; and terminal strips disposed at one end of and lying on opposite sides of said support member providing terminal conductors to which said sets of multiplied terminals and certain of the remaining terminals are connected for making connections outside said assembly.

3. A multi-relay assembly comprising, in combination, a support member comprising a bar, a plurality of aligned relays carried by said support member; each relay including a magnetic circuit formed by generally T and U shaped interfitting magnetic members with the ends of the U and of the top of the T spaced to form air gaps therebetween, said air gaps having their length extending longitudinally of said bar, a winding around the stem of the T, stationary and a plurality of movable contact means associated with each air gap, and terminals extending from said contact means to opposite sides, front and back, of said support member certain sets of which terminals are connected in multiple, the portions of each set of multiplied terminals to which connection is made being located substantially in a straight line longitudinally of the bar, a plurality of substantially straight bare conductors extending longitudinally of said bar, each interconnecting a set of aligned terminals; and terminal strips on opposite sides of said support member providing terminal bar conductors to which said sets of multiplied terminals and certain of the remaining terminals are connected for providing connections outside said assembly.

4. A multi-relay assembly comprising, in combination, a bar constituting a support member, a plurality of aligned relays carried by said support member; each relay including a magnetic circuit formed by generally T and U shaped interfitting magnetic members with the ends of the U and of the top of the T spaced to form air gaps therebetween, said air gaps having their length extending longitudinally of said bar, a winding around the stem of the T, stationary and movable contact means associated with each air gap, and terminals extending from said stationary contact means away from said support member, said movable contact means comprising conducting reeds stationarily mounted intermediate their ends and carrying contact members at one end to cooperate with said stationary contact means while the other ends form terminals and extend beyond said support member in a direction opposite to that in which the terminals from said stationary contact means extend, certain sets of said terminals being connected in multiple, the portions of each set of multiplied terminals to which connection is made being located substantially in a straight line for interconnection by a single substantially straight conductor, substantially straight bare conductors extending longitudinally of said bar, each interconnecting a set of aligned terminals; and terminal strips on opposite sides of said support member providing terminal conductors to certain of which said sets of multiple terminals are connected by said bare conductors, and additional longitudinally extending bare conductors connecting others of said terminal conductors and certain of the remaining relay terminals.

5. A multi-relay assembly comprising, in combination, a support member comprising a bar, and a plurality of aligned relays carried by said support member; each relay including a magnetic circuit formed by generally T and U shaped interfitting magnetic members with the ends of the U and of the top of the T spaced to form air gaps therebetween, said air gaps having their lengths extending longitudinally of the bar, the parts forming said U shaped magnetic member being common to all said relays, a winding around the stem of the T, stationary and movable contact means associated with each air gap, and

terminals extending from said contact means certain sets of which are connected in multiple, the portions of each set of multiplied terminals to which connection is made being located substantially in a straight line for interconnection by a single substantially straight conductor, and substantially straight bare conductors interconnecting said aligned multiple terminals.

6. A multi-relay assembly comprising, in combination, a support member comprising a bar, and a plurality of aligned relays carried by said support member; each relay including a winding, a magnetic circuit providing an air gap having its length extending longitudinally of said supporting bar, stationary and movable contact means, and terminals extending from said stationary contact means away from said support member, said movable contact means comprising conducting reeds stationarily mounted intermediate their ends and carrying contact members at one end to cooperate with said stationary contact means while the other ends form terminals and extend beyond said support member in a direction opposite to that in which the terminals from said stationary contact means extend, certain sets of said terminals being connected in multiple, the portions of each set of multiplied terminals to which connection is made being located substantially in a straight line for interconnection by a single substantially straight conductor substantially straight bare conductors connecting each set of said aligned terminals; stop means consisting of vitreous bars of insulation extending along said contact members carried by said reeds for uniformly spacing the same from their respective stationary contact means, and terminal strips on opposite sides of said support member providing terminal conductors to certain of which said sets of multiplied terminals are connected by said straight conductors and additional substantially straight longitudinally extending conductors connecting others of said terminal conductors and certain of the remaining relay terminals.

7. A multi-relay assembly comprising, in combination, a support member, a plurality of aligned relays carried by said support member; each relay including a magnetic circuit formed by generally T and U shaped interfitting magnetic members with the ends of the U and of the top of the T spaced to form air gaps therebetween, the parts forming said U shaped magnetic member being common to all said relays, a winding around the stem of the T, stationary and movable contact means associated with each air gap, and terminals extending from said stationary contact means away from said support member, said movable contact means comprising conducting reeds stationarily mounted intermediate their ends and carrying contact members at one end to cooperate with said stationary contact means while the other ends form terminals and extend beyond said support member in a direction opposite to that in which the terminals from said stationary contact means extend, certain sets of said terminals being connected in multiple, the portions of each set of multiplied terminals to which connection is made being located substantially in a straight line for interconnection by a single substantially straight conductor; stop means along each side of said U shaped magnetic member and common to all said contact members carried by said reeds therealong for uniformly spacing the same from their respective stationary contact means, and terminal strips on opposite sides of said support member to which said sets of multiplied terminals are connected.

tipled terminals and certain of the remaining terminals are connected.

8. A link for telephone exchange apparatus comprising, in combination, a bar serving as a support member, ten units relays and ten tens relays mounted in tandem on said support member; each relay including a winding, a magnetic circuit providing an air gap having its length extending longitudinally of the bar, and stationary and movable cooperating contact means having substantially coplanar terminals extending in opposite directions front and back of said bar, certain sets of which terminals are connected in multiple, the portions of each set of multiplied terminals to which connection is made being located in substantially a straight line longitudinally of the bar; and a single substantially straight conductor extending longitudinally of the bar and interconnecting each set of aligned multiplied terminals.

9. A link for telephone exchange apparatus comprising, in combination, a bar serving as a support member, ten units relays and ten tens relays mounted in tandem on said support member; each relay including a winding, a magnetic circuit providing an air gap having its length extending longitudinally of said supporting bar, and stationary and movable cooperating contact means having substantially coplanar terminals extending in opposite directions to opposite sides of said support member certain sets of which terminals are connected in multiple, the portions of each set of multiplied terminals to which connection is made being located substantially in a straight line for interconnection by a single substantially straight conductor; substantially straight conductors extending longitudinally of said bar, each interconnecting a set of aligned terminals, and terminal strips on opposite sides of said support member providing terminal conductors on the front side of the bar to certain of which said sets of multiplied terminals are connected by said straight conductors, and additional substantially straight longitudinally extending conductors connecting certain of said terminal conductors on the back side of said bar and certain of the remaining relay terminals.

10. A link for telephone exchange apparatus comprising, in combination, a bar serving as a support member, ten units relays and ten tens relays mounted in tandem on said support member; each relay including a winding, a magnetic circuit providing an air gap having its length extending longitudinally of said supporting bar, stationary and movable cooperating contact means, and terminals extending from said stationary contact means forwardly from said support member, said movable contact means comprising conducting reeds stationarily mounted intermediate their ends and carrying contact members at one end to cooperate with said stationary contact means while the other ends form terminals and extend behind said support member in a direction opposite to that in which the terminals from said stationary contact means extend, certain sets of said terminals being connected in multiple, the portions of each set of multiplied terminals to which connection is made being located substantially in a straight line for interconnection by a single substantially straight conductor; substantially straight conductors extending longitudinally of said bar, each interconnecting a set of aligned terminals, and terminal strips on opposite sides of said support member providing terminal conductors to certain

of which said sets of multiplied terminals are connected by said straight conductors, and additional substantially straight longitudinally extending conductors connecting others of said terminal conductors and certain of the remaining relay terminals.

11. A link for telephone exchange apparatus comprising, in combination, a bar serving as a support member, and ten units relays and ten tens relays mounted in tandem on said support member; each relay including a magnetic circuit formed by generally T and U shaped interfitting magnetic members with the ends of the U and the top of the T spaced to form air gaps therebetween, the longitudinal axis of said air gaps extending longitudinally of said supporting bar, a winding around the stem of the T, stationary and movable contact means associated with each air gap, and terminals extending from said contact means certain sets of which are connected in multiple, the portions of each set of multiplied terminals to which connection is made being located substantially in a straight line for interconnection by a single substantially straight conductor, and substantially straight conductors interconnecting said aligned multiple terminals.

12. A link for telephone exchange apparatus comprising, in combination, a bar serving as a support member, ten units relays and ten tens relays mounted in tandem on said support member; each relay including a magnetic circuit formed by generally T and U shaped interfitting magnetic members with the ends of the U and the top of the T spaced to form air gaps therebetween, the longitudinal axis of each of said air gaps extending longitudinally of said supporting bar, a winding around the stem of the T, stationary and movable contact means associated with each air gap, and terminals extending from said contact means to opposite sides of said support member certain sets of which are connected in multiple, the portions of each set of multiplied terminals to which connection is made being located substantially in a straight line for interconnection by a single substantially straight conductor; substantially straight conductors extending longitudinally of said bar, each interconnecting a set of aligned terminals, and terminal strips on opposite sides of said support member providing terminal conductors to certain of which said sets of multiplied terminals are connected by said straight conductors, and additional substantially straight longitudinally extending conductors connecting others of said terminal conductors and certain of the remaining relay terminals.

13. A link for telephone exchange apparatus comprising, in combination, a bar serving as a support member, ten units relays and ten tens relays mounted in tandem on said support member; each relay including a magnetic circuit formed by generally T and U shaped interfitting magnetic members with the ends of the U and the top of the T spaced to form air gaps therebetween, said air gaps having their longitudinal axes extending longitudinally of said supporting bar, a winding around the stem of the T, stationary and movable contact means associated with each air gap, and terminals extending from said stationary contact means forwardly from said support member, said movable contact means comprising conducting reeds stationarily mounted intermediate their ends and carrying contact members at one end to cooperate with said stationary contact means while the other ends form terminals and extend back of said support mem-

ber in a direction opposite to that in which the terminals from said stationary contact means extend, certain sets of said terminals being connected in multiple; the portions of each set of multiplied terminals to which connection is made being located substantially in a straight line for interconnection by a single substantially straight conductor; substantially straight conductors extending longitudinally of said bar, each interconnecting a set of aligned terminals, and terminal strips on opposite sides of said support member providing terminal conductors to certain of which said sets of multiplied terminals are connected by said straight conductors, and additional substantially straight longitudinally extending conductors connecting others of said terminal conductors and certain of the remaining relay terminals.

14. A link for telephone exchange apparatus comprising, in combination, a bar serving as a support member, and ten units relays and ten tens relays mounted in tandem on said support member; each relay including a magnetic circuit formed by generally T and U shaped interfitting magnetic members with the ends of the U and the top of the T spaced to form air gaps therebetween, the parts forming said U shaped magnetic member being common to all said relays, a winding around the stem of the T, stationary and movable contact means associated with each air gap, and terminals extending from said contact means, certain sets of which are connected in multiple; the portions of each set of multiplied terminals to which connection is made being located substantially in a straight line for interconnection by a single substantially straight conductor, and substantially straight conductors interconnecting said aligned multiple terminals.

15. A link for telephone exchange apparatus comprising, in combination, a bar serving as a support member, ten units relays and ten tens relays mounted in tandem on said support member; each relay including a winding, a magnetic circuit providing an air gap having its length extending longitudinally of said supporting bar, stationary and movable cooperating contact means, and terminals extending from said stationary contact means forwardly from said support member, said movable contact means comprising conducting reeds stationarily mounted intermediate their ends and carrying contact members at one end to cooperate with said stationary contact means while the other ends form terminals and extend back of said support member in a direction opposite to that in which the terminals from said stationary contact means extend, certain sets of said terminals being connected in multiple, the portions of each set of multiplied terminals to which connection is made being located substantially in a straight line for interconnection by a single substantially straight conductor; stop means consisting of bars of vitreous insulation extending along said contact members carried by said reeds for uniformly spacing the same from their respective stationary contact means, substantially straight conductors extending longitudinally of said bar, each interconnecting a set of aligned terminals, and terminal strips on opposite sides of said support member providing terminal conductors to certain of which said sets of multiplied terminals are connected by said straight conductors, and additional substantially straight longitudinally extending

conductors connecting others of said terminal conductors and certain of the remaining relay terminals.

16. A link for telephone exchange apparatus comprising, in combination, a support member, ten units relays and ten tens relays mounted in tandem on said support member; each relay including a magnetic circuit formed by generally T and U shaped interfitting magnetic members with the ends of the U and the top of the T spaced to form air gaps therebetween, the parts forming said U shaped magnetic member being common to all said relays, a winding around the stem of the T, stationary and movable contact means associated with each air gap, and terminals extending from said stationary contact means away from said support member, said movable contact means comprising conducting reeds stationarily mounted intermediate their ends and carrying contact members at one end to cooperate with said stationary contact means while the other ends form terminals and extend beyond said support member in a direction opposite to that in which the terminals from said stationary contact means extend, certain sets of said terminals being connected in multiple, the portions of each set of multiplied terminals to which connection is made being located substantially in a straight line for interconnection by a single substantially straight conductor; a glass rod extending along each side of said U shaped magnetic member and common to all said contact members carried by said reeds therealong for uniformly spacing the same from their respective stationary contact means, and terminal strips on opposite sides of said support member to which said sets of multiplied terminals and certain of the remaining terminals are connected.

17. In a multi-link assembly for telephone exchange apparatus, in combination, support members one for each link mounted in side-by-side relation, ten units relays and ten tens relays mounted in tandem on each support member; each relay including a winding, a magnetic circuit, and stationary and movable cooperating contact means having substantially coplanar terminals extending in opposite directions certain of which are multiplied with corresponding ones of relays of the other links to form sets of multiplied terminals; the portions of each set of multiplied terminals to which connection is made being located substantially in a straight line; and a single substantially straight conductor interconnecting each set of multiplied terminals.

18. In a multi-link assembly for telephone exchange apparatus, in combination, support members one for each link mounted in side-by-side relation, ten units relays and ten tens relays mounted in tandem on each support member; each relay including a winding, a magnetic circuit, and stationary and movable cooperating contact means having substantially coplanar terminals extending to opposite sides of the support member individual thereto certain of which are multiplied with corresponding ones of relays of the other links to form sets of multiplied terminals, the portions of each set of multiplied terminals to which connection is made being located in substantially a straight line; a single substantially straight conductor interconnecting each set of multiplied terminals, and terminal strip means common to all of the links to which said conductors are connected.

19. In a multi-link assembly for telephone exchange apparatus, in combination, support mem-

bers one for each link mounted in side-by-side relation, ten units relays and ten tens relays mounted in tandem on each support member; each relay including a winding, a magnetic circuit, stationary and movable cooperating contact means, and terminals extending from said stationary contact means away from the support member individual thereto, said movable contact means comprising conducting reeds stationarily mounted intermediate their ends and carrying contact members at one end to cooperate with said stationary contact means while the other ends form terminals and extend beyond the support member individual thereto in a direction opposite to that in which the terminals from said stationary contact means extend, certain of said terminals being multiplied with corresponding ones of relays of the other links to form sets of multiplied terminals, the portions of each set of multiplied terminals to which connection is made being located substantially in a straight line; a single substantially straight conductor interconnecting each set of multiplied terminals, and terminal strip means common to all of the links to which said conductors are connected.

20. In a multi-link assembly for telephone exchange apparatus, in combination, support members one for each link mounted in side-by-side relation, ten units relays and ten tens relays mounted in tandem on each support member; each relay including a magnetic circuit formed by generally T and U shaped interfitting magnetic members with the ends of the U and the top of the T spaced to form air gaps therebetween, a winding around the stem of the T, stationary and movable contact means associated with each air gap, and terminals extending from said contact means certain of which are multiplied with corresponding ones of relays of the other links to form sets of multiplied terminals, the portions of each set of multiplied terminals to which connection is made being located substantially in a straight line; and a single substantially straight conductor interconnecting each set of multiplied terminals.

21. In a multi-link assembly for telephone exchange apparatus, in combination, support members one for each link mounted in side-by-side relation, ten units relays and ten tens relays mounted in tandem on each support member; each relay including a magnetic circuit formed by generally T and U shaped interfitting magnetic members with the ends of the U and the top of the T spaced to form air gaps therebetween, a winding around the stem of the T, stationary and movable contact means associated with each air gap, and terminals extending from said contact means to opposite sides of the support member individual thereto certain of which are multiplied with corresponding ones of relays of the other links to form sets of multiplied terminals, the portions of each set of multiplied terminals to which connection is made being located in substantially a straight line; a single substantially straight conductor interconnecting each set of multiplied terminals, and terminal strip means common to all of the links to which said conductors are connected.

22. In a multi-link assembly for telephone exchange apparatus, in combination, support members one for each link mounted in side-by-side relation, ten units relays and ten tens relays mounted in tandem on each support member; each relay including a magnetic circuit formed

by generally T and U shaped interfitting magnetic members with the ends of the U and the top of the T spaced to form air gaps therebetween, a winding around the stem of the T, stationary and movable contact means associated with each air gap, and terminals extending from said stationary contact means away from the support member individual thereto, said movable contact means comprising conducting reeds stationarily mounted intermediate their ends and carrying contact members at one end to cooperate with said stationary contact means while the other ends form terminals and extend beyond the support member individual thereto in a direction opposite to that in which the terminals from said stationary contact means extend, certain of said terminals being multiplied with corresponding ones of relays of the other links to form sets of multiplied terminals, the portions of each set of multiplied terminals to which connection is made being located substantially in a straight line; a single substantially straight conductor interconnecting each set of multiplied terminals, and terminal strip means common to all of the links to which said conductors are connected.

23. In a multi-link assembly for telephone exchange apparatus, in combination, support members one for each link mounted in side-by-side relation, ten units relays and ten tens relays mounted in tandem on each support member; each relay including a magnetic circuit formed by generally T and U shaped interfitting magnetic members with the ends of the U and the top of the T spaced to form air gaps therebetween, the parts forming said U shaped magnetic member being common to all of the relays of each link, a winding around the stem of the T, stationary and movable contact means associated with each air gap, and terminals extending from said contact means certain of which are multiplied with corresponding ones of relays of the other links to form sets of multiplied terminals, the portions of each set of multiplied terminals to which connection is made being located substantially in a straight line; and a single substantially straight conductors interconnecting each set of multiplied terminals.

24. In a multi-link assembly for telephone exchange apparatus, in combination, support members one for each link mounted in side-by-side relation, ten units relays and ten tens relays mounted in tandem on each support member; each relay including a winding, a magnetic circuit, stationary and movable cooperating contact means, and terminals extending from said stationary contact means away from the support member individual thereto, said movable contact means comprising conducting reeds stationarily mounted intermediate their ends and carrying contact members at one end to cooperate with said stationary contact means while the other ends form terminals and extend beyond the support member individual thereto in a direction opposite to that in which the terminals from said stationary contact means extend, certain of said terminals being multiplied with corresponding ones of relays of the other links to form sets of multiplied terminals, the portions of each set of multiplied terminals to which connection is made being located substantially in a straight line; stop means extending along said contact members carried by said reeds for uniformly spacing the same from their respective stationary contact means, a single substantially straight

conductor interconnecting each set of multiplied terminals, and terminal strip means common to all of the links to which said conductors are connected.

25. In a multi-link assembly for telephone exchange apparatus, in combination, support members one for each link mounted in side-by-side relation, ten units relays and ten tens relays mounted in tandem on each support member; each relay including a magnetic circuit formed by generally T and U shaped interfitting magnetic members with the ends of the U and the top of the T spaced to form air gaps therebetween, the parts forming said U shaped magnetic member being common to all of the relays of each link, a winding around the stem of the T, stationary and movable contact means associated with each air gap, and terminals extending from said stationary contact means away from the support member individual thereto, said movable contact means comprising conducting reeds stationarily mounted intermediate their ends and carrying contact members at one end to cooperate with said stationary contact means while the other ends form terminals and extend beyond the support member individual thereto in a direction opposite to that in which the terminals from said stationary contact means extend, certain of said terminals being multiplied with corresponding ones of relays of the other links to form sets of multiplied terminals, the portions of each set of multiplied terminals to which connection is made being located substantially in a straight line; a glass rod extending along each side of the U shaped magnetic member of each link and common to all said contact members carried by said reeds therealong for uniformly spacing the same from their respective stationary contact means, a single substantially straight conductor interconnecting each set of multiplied terminals, and terminal strip means common to all of the links to which said conductors are connected.

26. In a multi-link assembly for telephone exchange apparatus, in combination, support members one for each link mounted vertically in side-by-side relation, ten units relays and ten tens relays mounted in tandem on each support member; each relay including a winding, a magnetic circuit, and stationary and movable cooperating contact means having substantially coplanar terminals extending horizontally in opposite directions certain sets of which in each link are vertically connected in multiple and certain others of which are horizontally connected in multiple with corresponding ones of relays of the other links to form sets of multiplied terminals, the portions of each set of multiplied terminals to which connection is made being located substantially in a straight line; and a single substantially straight conductor interconnecting each set of multiplied terminals.

27. In a multi-link assembly for telephone exchange apparatus, in combination, support members one for each link mounted vertically in side-by-side relation, ten units relays and ten tens relays mounted in tandem on each support member; each relay including a winding, a magnetic circuit, and stationary and movable cooperating contact means having substantially coplanar terminals extending horizontally to opposite sides of the support member individual thereto certain sets of which in each link are vertically connected in multiple and certain others of which are horizontally connected in

multiple with corresponding ones of relays of the other links to form sets of multiplied terminals, the portions of each set of multiplied terminals to which connection is made being located substantially in a straight line; a single substantially vertical conductor interconnecting each set of multiplied terminals of each link, terminal strip means on opposite sides of each support member to which the vertically multiplied terminals and certain of the remaining terminals of each link are connected, a single substantially horizontal conductor interconnecting each set of multiplied terminals of all of the links, and terminal strip means common to all of the links to which the horizontally multiplied terminals are connected.

28. In a multi-link assembly for telephone exchange apparatus, in combination, support members one for each link mounted vertically in side-by-side relation, ten units relays and ten tens relays mounted in tandem on each support member; each relay including a winding, a magnetic circuit, and stationary and movable cooperating contact means, and terminals extending horizontally from said stationary contact means away from the support member individual thereto, said movable contact means comprising horizontal conducting reeds stationarily mounted intermediate their ends and carrying contact members at one end to cooperate with said stationary contact means while the other ends form terminals and extend beyond the support means individual thereto in a direction opposite to that in which the terminals from said stationary contact means extend, certain sets of said terminals in each link being vertically connected in multiple and certain others of said terminals in each link being horizontally connected in multiple with corresponding ones of relays of the other links to form sets of multiplied terminals, the portions of each set of multiplied terminals to which connection is made being located substantially in a straight line; a single substantially vertical conductor interconnecting each set of multiplied terminals of each link, terminal strip means on opposite sides of each support member to which the vertically multiplied terminals and certain of the remaining terminals of each link are connected, a single substantially horizontal conductor interconnecting each set of multiplied terminals of all of the links, and terminal strip means common to all of the links to which the horizontally multiplied terminals are connected.

29. In a multi-link assembly for telephone exchange apparatus, in combination, support members one for each link mounted vertically in side-by-side relation, ten units relays and ten tens relays mounted in tandem on each support member; each relay including a magnetic circuit formed by generally T and U shaped interfitting magnetic members with the ends of the U and the top of the T spaced to form air gaps therebetween, stationary and movable contact means associated with each air gap, and substantially coplanar terminals extending horizontally in opposite directions from said stationary and movable contact means respectively certain sets of which in each link are vertically connected in multiple and certain others of which are horizontally connected in multiple with corresponding ones of relays of the other links to form sets of multiplied terminals, the portions of each set of multiplied terminals to which connection is made being located substantially in a straight

line; and a single substantially straight conductor interconnecting each set of multiplied terminals.

30. In a multi-link assembly for telephone exchange apparatus, in combination, support members one for each link mounted vertically in side-by-side relation, ten units relays and ten tens relays mounted in tandem on each support member; each relay including a magnetic circuit formed by generally T and U shaped interfitting magnetic members with the ends of the U and the top of the T spaced to form air gaps therebetween, stationary and movable contact means associated with each air gap, and substantially coplanar terminals extending horizontally in opposite directions from said stationary and movable contact means respectively to opposite sides of the support member individual thereto certain sets of which in each link are vertically connected in multiple and certain others of which are horizontally connected in multiple with corresponding ones of relays of the other links to form sets of multiplied terminals, the portions of each set of multiplied terminals to which connection is made being located substantially in a straight line; a single substantially vertical conductor interconnecting each set of multiplied terminals of each link, terminal strip means on opposite sides of each support member to which the vertically multiplied terminals and certain of the remaining terminals of each link are connected, a single substantially horizontal conductor interconnecting each set of multiplied terminals of all of the links, and terminal strip means common to all of the links to which the horizontally multiplied terminals are connected.

31. In a multi-link assembly for telephone exchange apparatus, in combination, support members one for each link mounted vertically in side-by-side relation, ten units relays and ten tens relays mounted in tandem on each support member; each relay including a magnetic circuit formed by generally T and U shaped interfitting magnetic members with the ends of the U and the top of the T spaced to form air gaps therebetween, stationary and movable contact means associated with each air gap, and terminals extending horizontally from said stationary contact means away from the support member individual thereto, said movable contact means comprising horizontal conducting reeds stationarily mounted intermediate their ends and carrying contact members at one end to cooperate with said stationary contact means while the other ends form terminals and extend beyond the support means individual thereto in a direction opposite to that in which the terminals from said stationary contact means extend, certain sets of said terminals in each link being vertically connected in multiple and certain others of said terminals in each link being horizontally connected in multiple with corresponding ones of relays of the other links to form sets of multiplied terminals, the portions of each set of multiplied terminals to which connection is made being located substantially in a straight line; a single substantially vertical conductor interconnecting each set of multiplied terminals of each link, terminal strip means on opposite sides of each support member to which the vertically multiplied terminals and certain of the remaining terminals of each link are connected, a single substantially horizontal conductor interconnecting each set of multiplied terminals of all of the links, and terminal strip means common to all of the links to which the horizontally multiplied terminals are connected.

means common to all of the links to which the horizontally multiplied terminals are connected.

32. In a multi-link assembly for telephone exchange apparatus, in combination, support members one for each link mounted vertically in side-by-side relation, ten units relays and ten tens relays mounted in tandem on each support member; each relay including a magnetic circuit formed by generally T and U shaped interfitting magnetic members with the ends of the U and the top of the T spaced to form air gaps therebetween, the parts forming said U shaped magnetic member being common to all of the relays of each link, stationary and movable contact means associated with each air gap, and substantially coplanar terminals extending horizontally in opposite directions from said stationary and movable contact means respectively certain sets of which in each link are vertically connected in multiple and certain others of which are horizontally connected in multiple with corresponding ones of relays of the other links to form sets of multiplied terminals, the portions of each set of multiplied terminals to which connection is made being located substantially in a straight line; and a single substantially straight conductor interconnecting each set of multiplied terminals.

33. In a multi-link assembly for telephone exchange apparatus, in combination, support members one for each link mounted vertically in side-by-side relation, ten units relays and ten tens relays mounted in tandem on each support member; each relay including a winding, a magnetic circuit, and stationary and movable cooperating contact means, and terminals extending horizontally from said stationary contact means away from the support member individual thereto, said movable contact means comprising horizontal conducting reeds stationarily mounted intermediate their ends and carrying contact members at one end to cooperate with said stationary contact means while the other ends form terminals and extend beyond the support means individual thereto in a direction opposite to that in which the terminals from said stationary contact means extend, certain sets of said terminals in each link being vertically connected in multiple and certain others of said terminals in each link being horizontally connected in multiple with corresponding ones of relays of the other links to form sets of multiplied terminals, the portions of each set of multiplied terminals to which connection is made being located substantially in a straight line; stop means extending along said contact members carried by said reeds for uniformly spacing the same from their respective stationary contact means, a single substantially vertical conductor interconnecting each set of multiplied terminals of each link, terminal strip means on opposite sides of each support member to which the vertically multiplied terminals and certain of the remaining terminals of each link are connected, a single substantially horizontal conductor interconnecting each set of multiplied terminals of all of the links, and terminal strip means common to all of the links to which the horizontally multiplied terminals are connected.

34. In a multi-link assembly for telephone exchange apparatus, in combination, support members one for each link mounted vertically in side-by-side relation, ten units relays and ten tens relays mounted in tandem on each support member; each relay including a magnetic circuit formed by generally T and U shaped interfitting

magnetic members with the ends of the U and the top of the T spaced to form air gaps therebetween, the parts forming said U shaped magnetic member being common to all of the relays of each link, stationary and movable contact means associated with each air gap, and terminals extending horizontally from said stationary contact means away from the support member individual thereto, said movable contact means comprising horizontal conducting reeds stationarily mounted intermediate their ends and carrying contact members at one end to cooperate with said stationary contact means while the other ends form terminals and extend beyond the support means individual thereto in a direction opposite to that in which the terminals from said stationary contact means extend, certain sets of said terminals in each link being vertically connected in multiple and certain others of said terminals in each link being horizontally connected in multiple with corresponding ones of relays of the other links to form sets of multiplied terminals, the portions of each set of multiplied terminals to which connection is made being located substantially in a straight line; a glass rod extending along each side of the U shaped magnetic member of each link and common to all said contact members carried by said reeds therealong for uniformly spacing the same from their respective stationary contact means, a single substantially vertical conductor interconnecting each set of multiplied terminals of each link, terminal strip means on opposite sides of each support member to which the vertically multiplied terminals and certain of the remaining terminals of each link are connected, a single substantially horizontal conductor interconnecting each set of multiplied terminals of all of the links, and terminal strip means common to all of the links to which the horizontally multiplied terminals are connected.

35. In telephone exchange apparatus, in combination, a plurality of links each including a plurality of relays having relatively movable contact members with terminal connectors certain sets of which are multiplied, the portions of each set of terminal connectors to which connection is made being located substantially in a straight line, and a substantially straight conductor interconnecting each set of multiplied terminal connectors, the conductors interconnecting the sets of multiplied terminal connectors being disposed in insulated spaced relation with substantially only an air dielectric therebetween whereby the capacity thereof is substantially zero.

36. In telephone exchange apparatus, in combination, a plurality of links each including a plurality of relays having relatively movable and engageable contact members with substantially only the portions of the contact members adapted to be mutually engaged in parallel relation whereby the capacity therebetween is substantially zero, terminal connectors for said contact members certain sets of which are multiplied, the portions of each set of terminal connectors to which connection is made being located substantially in a straight line, and a substantially straight conductor interconnecting each set of multiplied terminal connectors, the conductors interconnecting the sets of multiplied terminal connectors being disposed in insulated spaced relation with substantially only an air dielectric therebetween whereby the capacity thereof is substantially zero.

37. In telephone exchange apparatus, in com-

bination; a plurality of links each including a plurality of relays each having relatively stationary and movable and engageable cooperating contact members with substantially only the portions of the contact members adapted to be mutually engaged in parallel relation whereby the capacity therebetween is substantially zero, armature means carried by each movable contact member, and electromagnetic means cooperating with said armature means for operating said movable contact members into engagement with their respective stationary contact members; terminal connectors for said contact members certain sets of which are multiplied, the portions of each set of terminal connectors to which connection is made being located substantially in a straight line, and a substantially straight conductor interconnecting each set of multiplied terminal connectors, the conductors interconnecting the sets of multiplied terminal connectors being disposed in insulated spaced relation with substantially only an air dielectric therebetween whereby the capacity thereof is substantially zero.

38. In telephone exchange apparatus, in combination; a plurality of links each including a plurality of relays each having relatively stationary and movable and engageable cooperating contact members with substantially only the portions of the contact members adapted to be mutually engaged in parallel relation whereby the capacity therebetween is substantially zero, armature means carried by each movable contact member, and electromagnetic means cooperating with said armature means for operating said movable contact members into engagement with their respective stationary contact members, the mass of said movable contact members and armature means being relatively small as compared to the force of attraction capable of being exerted by said electromagnetic means whereby the contact engagement between said contact members is effected without chattering and noise on the circuit in which they are connected is substantially reduced; terminal connectors for said contact members certain sets of which are multiplied, the portions of each set of terminal connectors to which connection is made being located substantially in a straight line, and a substantially straight conductor interconnecting each set of multiplied terminal connectors, the conductors interconnecting the sets of multiplied terminal connectors being disposed in insulated spaced relation with substantially only an air dielectric therebetween whereby the capacity thereof is substantially zero.

39. In a selective interconnecting device, a plurality of parallel conductors in one plane, a plurality of parallel conductors in another plane and spaced from, but substantially in a right angle relation to the first mentioned plane, a substantially straight interconnecting conductor attached to each conductor in the first mentioned plane extending to a different conductor in the second mentioned plane on a line which constitutes substantially the shortest distance between the two conductors to be interconnected, a break in the interconnecting conductor, an independent circuit-closer for each of the said breaks, and means for operating any of said circuit closers, as described.

40. In a selective interconnecting device, a plurality of parallel conductors in one plane, a plurality of parallel conductors in another plane and spaced from, but at right angles thereto, whereby each of the conductors in the second plane

crosses each of the conductors in the first mentioned plane, a substantially straight normally open interconnecting conductor extending between each of the first-mentioned conductors and a different one of the second-mentioned conductors on a line which constitutes substantially the minimum distance between the two conductors to be interconnected, an independent group operated electro-magnetic circuit-closer for each of said normal breaks, whereby any conductor in the first-mentioned plane may be connected to any conductor in the second-mentioned plane.

41. In a circuit interconnector, a plurality of parallel conductors in one plane, another plurality of parallel conductors in another plane, all of said second-mentioned conductors crossing those of the first-mentioned conductors substantially at right angles, but not in contact therewith, the said groups being separated from one another spacially, a substantially straight interconnecting conductor extending from each of said first-mentioned conductors to each of said second-mentioned conductors approximately in the line of minimum distance between said conductors at their crossing, a normally-open break in each of the interconnecting conductors, an independent group operated electro-magnetic circuit-closer for each break, each of the circuit-closers being located physically between the two said groups of conductors, and means for operating any of the said circuit-closers.

42. In an interconnector, two groups of straight wire conductors in different planes respectively crossing each other, a direct substantially straight permanent interconnecting conductor extending from each crossing conductor of one group to a different crossing conductor of the other group on a line which is substantially the minimum distance between them, a normally-open break in said interconnecting conductor, an independent electro-magnetic circuit-closer therefor, and selective means for operating independently any one of said circuit-closers, as described.

43. In a selective interconnector, a plurality of parallel straight line-conductors in one plane, another group of parallel straight line or link-conductors in another plane crossing said first-mentioned conductors but not in electrical contact therewith, a substantially straight cross-connecting conductor extending from each of said first-mentioned conductors to a different one of said second-mentioned conductors on a line which is substantially the minimum distance between them, said cross connecting conductor being composed in part of a contact-anvil, a contact-point and a reed carrying said contact-point, said contact-point and said contact-anvil being normally separated, and an independent operating-magnet for closing any contact upon its anvil, as described.

44. In a selective interconnector, a plurality of line-conductors in one plane, a plurality of line or link-conductors in another plane crossing said first-mentioned conductor but not in electrical contact therewith, an interconnecting conductor leading from each of said first-mentioned conductors to a different one of each second-mentioned crossing conductors on a line which is substantially the shortest distance between them, said interconnecting conductor being composed in part of a contact-anvil, a contact-point, a flexible reed carrying the contact-point, an independent, individual armature of small mass carried upon said reed, a magnet for operating said armature,

said contact-anvil, reed and magnet being located in the space between the planes of the two said groups of crossing conductors, and means for selectively operating any one of said electro-magnets, whereby any one of said first-mentioned conductors may be connected with any one of said second-mentioned conductors, as described.

45. In a telephone line-selector, a group of telephone line-conductors consisting of straight parallel wires in a plane, a group of line or link conductors consisting of like parallel straight wire conductors in a plane at right angles thereto, whereby each one of said first-mentioned conductors crosses each member of said second group, substantially straight independent interconnecting conductors extending from each of said first-mentioned line-conductors to a different one of said second-mentioned line-conductors on a line which is substantially the minimum distance between them, said interconnecting conductor being composed in part of a contact-anvil, a contact-point, said point being carried upon a flexible reed, an armature of small mass carried on said reed, an independent electro-magnet controlling each armature in combination with a number-impulse device for each line, a number-register and sender selectively controlling all said operating magnets, whereby any telephone subscriber may selectively operate any of said circuit-closers and connect his line to another line or link.

46. In a telephone system, the combination of a vertical longitudinal supporting bar, a relay comprising a horizontal core supported on front of and at right angles to the bar, an outer pole-piece for the outer end of the core, said pole-piece having edges parallel to the longitudinal axis of the bar and a pair of platelike polepieces for the inner end of the core, said platelike pole-pieces lying on opposite sides of the core and having their outer edges separated from the edges of the outer polepiece by air gaps, a series of parallel straight horizontal wire reeds lying in parallel planes disposed laterally of the respective platelike pole pieces, said reeds having fixed on their upper ends barlike armatures extending lengthwise of the reeds and disposed transversely across the corresponding air gaps, a vertical bar of insulation lying at the side of each platelike polepiece and embedding and rigidly holding the corresponding reeds intermediate their length, the inner ends of the reeds extending back of said bar to predetermined points, a series of substantially straight bare conductors extending longitudinally of the supporting bar and being disposed parallel to each other in substantially parallel planes at opposite lateral sides of and back of the supporting bar, insulators disposed back of the supporting bar holding said parallel conductors in fixed position relative to each other and to said supporting bar, the inner ends of certain ones of the vertical reeds being connected to selected ones of said parallel conductors, a vertically extending contact supporting bar of insulation disposed upon the outer polepiece, stationary contacts for cooperation with said armatures respectively mounted on each lateral side of the latter bar of insulation, said contacts having outwardly extending terminals disposed in parallel vertical planes lying at the lateral sides of the said latter bar of insulation, a series of bare substantially straight conductors extending longitudinally of said supporting bar disposed in two parallel vertical planes adjacent the corresponding outwardly extending ter-

minals, said terminals extending to predetermined points and being connected to predetermined ones of said adjacent vertically extending conductors, and insulators holding said last named longitudinal conductors in fixed relation to each other and to said relay.

47. The combination of a series of relays of the structure defined in claim 46 mounted in alignment on said supporting bar with their wire reeds on each side of the supporting bar in the same plane, and their terminals at each side of the supporting bar of insulation in the same plane, and having their reed terminals connected to selected ones of the inner series of longitudinal conductors and having their stationary contact terminals connected to selected ones of the outer series of longitudinal conductors.

48. In combination, a vertical supporting bar, a relay mounted on said bar and having a stationary magnet structure providing an air gap at each side thereof extending longitudinally of said bar, armatures disposed in planes on opposite sides of the magnet structure and comprising oblong magnetic bars extending horizontally across the air gaps transversely thereof, wire reeds having said armatures fixed upon the upper ends thereof, vertical supporting bars of insulation imbedding said reeds intermediate their ends, said bars being fixedly mounted relative to the stationary magnet structure, the inner ends of the reeds extending back of the supporting bar, a series of substantially straight horizontally extending bare conductors extending transversely of the supporting bar and disposed in substantially a vertical plane, the lower ends of said reeds being connected to corresponding ones of said transverse horizontal conductors, a vertically extending stationary contact supporting bar of insulation supported on the outer end of the stationary magnet structure, a series of stationary contacts on each side of the magnet structure, said contacts being embedded in opposite lateral sides of said contact supporting bar, said stationary contacts having horizontally extending terminals lying in substantially parallel planes on opposite lateral sides of the contact supporting bar, substantially straight bare conductors extending longitudinally of the supporting bar and lying in vertical planes adjacent the planes of the contact terminals, said contact terminals extending selected distances forwardly to register with selected ones of said bare vertically extending conductors and having offset ends to extend into engagement with the selected straight bare conductors.

49. In the combination of claim 48 of a second set of coplanar vertical conductors disposed transversely of said supporting bar, a second relay as defined in said claim and aligned edge to edge on the supporting bar with said first defined relay, said second relay having its reed terminals connected to the inner vertical conductors and its stationary contact terminals connected to the outer vertical conductors.

50. In a relay type link for telephone exchange apparatus, the combination of a first group of substantially coplanar parallel vertically extending conductors disposed in a substantially vertical plane, a second group of substantially coplanar parallel horizontally extending conductors disposed behind said first group of conductors in a vertical plane and the conductors of said second group being disposed substantially at right angles to the plane of said first group of conductors but spaced from them, insulating sup-

ports for the conductors of each group, substantially straight parallel coplanar interconnecting conductors extending in substantially straight horizontal lines between conductors of the first group and corresponding conductors of the second group, said interconnecting conductors each including a stationary and a movable relay contact, and a common relay magnet structure disposed on the space between said groups of vertical and horizontal conductors for operating a group of said movable relay contacts in unison.

51. The combination of claim 50 wherein said interconnecting conductors comprise outer sections and inner sections, the outer sections comprising stationary contacts all disposed in a vertical line substantially parallel to the plane of the first group of conductors, and terminal members for the contacts extending from the contacts horizontally at one side of the plane of the conductors of the first group, said terminal members extending various distances outwardly and having laterally offset end portions by which they engage and are individually connected to the corresponding ones of the conductors of the first group, the inner sections comprising a bank of horizontally extending substantially coplanar wire reeds, each reed having an armature bar at its outer end adapted to engage the stationary contact of the corresponding outer section, a common insulating support for said reeds engaging them intermediate their ends, the inner ends of the reeds being connected to corresponding ones of said conductors of the second group, and a common insulating support for the aligned stationary contacts, said common supports being rigidly connected to the common magnet structure.

52. In a relay type link for telephone exchange apparatus, the combination of a first group of substantially coplanar parallel vertically extending conductors disposed in a substantially vertical plane, a second group of substantially coplanar parallel horizontally extending conductors disposed behind said first group of conductors in a vertical plane and the conductors of said second group being disposed substantially at right angles to the plane of said first group of conductors, insulating supports for the conductors of each group, a first set of substantially parallel coplanar interconnecting conductors extending in substantially straight horizontal lines between conductors of the first group and corresponding conductors of the second group, a third group of substantially coplanar parallel vertically extending conductors disposed in substantially a vertical plane behind the conductors of the second set, a second set of substantially parallel coplanar interconnecting conductors extending in substantially straight horizontal lines between certain ones of the conductors of the first set, and corresponding ones of the conductors of the third set, said interconnecting conductors of both sets being coplanar and each including a stationary and a movable relay contact and a common tens relay magnet structure having a narrow vertically extending air gap for operating said movable relay contacts of both sets of interconnecting conductors in common.

53. In a link for telephone exchange apparatus the combination of a first group of substantially coplanar parallel vertically extending conductors disposed in substantially a vertical plane, a series of second groups of substantially coplanar parallel vertically extending conductors disposed in a substantially vertical plane below

and substantially parallel to the conductors of the first group, insulating supports for each group of conductors, substantially parallel coplanar interconnecting conductors extending in substantially straight horizontal lines between certain ones of the conductors of the first group and certain ones of the conductors of the second group, said interconnecting conductors each including a stationary and a movable relay contact and a common relay magnet structure for operating a group of said movable relay contacts in unison.

54. In a link for telephone exchange apparatus the combination of a horizontally extending bar constituting a support, a first bank of external terminals at one end of said bar and in front of the same, said terminals being disposed in rows longitudinally of the bar, a first group of substantially coplanar parallel vertically extending conductors disposed in a substantially vertical plane disposed in front of the support and having insulating support means rigid with the said support, the conductors of the first group being connected at their upper ends with said external terminals, a second group of substantially coplanar parallel horizontally extending conductors disposed in a vertical plane behind said support and having insulating supporting means for holding said conductors in spaced relation, said conductors of the second group extending substantially at right angles to the plane of the conductors of the first group, a first series of groups of substantially parallel coplanar tens interconnecting conductors extending in substantially straight lines horizontally between conductors of the first group and certain corresponding ones of the conductors of the second group, said interconnecting conductors each including a stationary and a movable relay contact, a series of relay magnet structures mounted in tandem on said support, said relay magnet structures comprising a series of unit relays and a series of tens relays, a second bank of external terminals at said one end of said supporting bar and back of the same, a third group of substantially coplanar parallel vertically extending conductors disposed in a substantially vertical plane behind said second groups of conductors, the plane of said third group of conductors being substantially normal to the plane of the second groups of conductors, a second series of groups of substantially parallel coplanar unit interconnecting conductors extending in substantially straight lines horizontally between conductors of the first group and certain corresponding ones of the conductors of the third group, said second series of interconnecting conductors each including a stationary and a movable relay contact, each of the unit relay magnet structures operating in unison certain groups of said movable relay contacts of said second series of interconnecting conductors, and each of the tens relay magnet structures operating in unison certain groups of said movable relay contacts of said first series of interconnecting conductors.

55. In a link of the class described, a supporting bar, a series of multiple relays mounted on the front of said bar in end to end alignment, each relay having a magnet frame providing an air gap the length of which extends longitudinally of the bar, a plurality of armatures mounted for simultaneous attraction, said armatures extending in parallel across said air gap and having individual terminals extending back of said supporting bar, stationary contacts for said armatures having terminals extending forwardly of

the relays mounted on said bar, terminal strips mounted on front and back of said bar respectively, said strips having terminal bars supported in insulated relation, said terminal bars having inner and outer ends, the outer ends being arranged for making external connections, bare conductors connected to said inner ends and extending in substantially straight runs longitudinally of the bar and comprising a bank of conductors supported in substantially coplanar relation in front of the bar, and a bank of conductors supported in substantially coplanar relation behind the bar, certain conductors of said first bank connecting aligned contact terminals in multiple, and certain conductors of said second bank connecting corresponding armature terminals to said terminal bars back of the supporting bar, and blocks of insulation supporting said bare conductors of both banks in fixed relation to said bar.

56. In a telephone exchange system a relay selector and connector unit comprising an open supporting frame, a series of parallel selector supporting bars attached at opposite ends to said frame, a corresponding series of parallel connector supporting bars also attached at opposite ends to said frame and being parallel to said selector bars, terminal strips on front and back of each bar, said terminal strips being disposed at the ends of the bars, said strips having banks of terminals, a group of ten tens relays and a group of ten units relays disposed in endwise alignment on each bar, said relays having each a plurality of armatures and stationary contacts therefor on each side of the bar, terminals for the armatures and terminals for the stationary contacts extending in substantially parallel vertical planes alongside the sides of the bar, the corresponding tens relays on said bars being aligned horizontally with certain of their armature terminals aligned in horizontal rows, a group of horizontally disposed substantially straight multiple line conductors disposed back of each horizontally aligned group of tens relays, each multiple line conductor being connected to a horizontal row of armature terminals, the stationary contact terminals of the units relays and of the tens relays extending outwardly to predetermined positions in vertical alignment, corresponding terminals of the tens relay on the same bar being aligned in straight vertical rows for multiple connection by individual substantially straight conductors, individual substantially straight conductors connecting said contacts in each vertical row with corresponding bank terminals in the bank of terminals in front of the corresponding supporting bar, said unit relays on each bar having stationary relay contact terminals aligned with and connected to corresponding ones of the said vertical conductors, and a group of substantially straight vertically extending conductors back of each supporting bar and aligned with a row of armature terminals of the units relays on said bar, said conductors connecting certain ones of the armature terminals of the units relays with the rear bank terminals of the corresponding supporting bar.

57. The combination with claim 56 of banks of line terminal strips on the supporting frame having bank terminals connected with said groups of multiple line conductors and providing connecting means for telephone line conductors leading to the selector-connector unit.
